Primary Examiner—Cathron Brooks(74) *Attorney, Agent, or Firm*—Cohn, Powell & Hind**CLAIM**

The ornamental design for a merchandiser with curved ends, as shown and described.

DESCRIPTION

FIG. 1 is a perspective view of a merchandiser with curved ends showing my new design;

FIG. 2 is a front elevational view of FIG. 1;

FIG. 3 is a top plan view of FIG. 1;

FIG. 4 is a left side elevational view of FIG. 1;

FIG. 5 is a right side elevational view of FIG. 1;

FIG. 6 is a rear elevational view of FIG. 1; and,

FIG. 7 is a bottom plan view of FIG. 1.

The broken lines shown in the drawings are for illustrative purposes only and form no part of the claimed design.
